UNITED STATES PATENT OFFICE.

JOSEPH WILMOT SMITH, OF NEW YORK, N. Y.

GARTER.

1,165,457.

Specification of Letters Patent. Patented Dec. 28, 1915.

Application filed January 27, 1915. Serial No. 4,580.

To all whom it may concern:

Be it known that I, JOSEPH WILMOT SMITH, a citizen of the United States, residing at New York, in the county of New York and State of New York, have invented new and useful Improvements in Garters, of which the following is a specification.

This invention relates to a garment supporter, and particularly to hose supporters. Such hose supporters, when employed for supporting half hose or socks are frequently applied to the bare limb, and they usually embody certain parts which it is advisable or necessary to form of metal. It is also advisable to prevent, if possible, such a metal part from coming in direct contact with the flesh of the limb. For this reason in hose supporters or garters of simple construction difficulty is experienced in producing a garter in which the metal parts are prevented from coming in contact with the limb.

The principal object of the present invention is to produce a garment supporter of very simple construction which can be readily applied and adjusted on the limb, and which embodies a metal part, but having a very simple construction operating to prevent the metal from coming in contact with the limb.

A further object of the invention is to produce a garment supporter having a very neat and sanitary appearance, particularly with respect to the member employed to prevent the contact of the metal with the limb.

A further object of the invention is to provide a protecting member which, while it effectually prevents contact with the metal, will also be a non-absorbent and adapted to be easily cleaned.

The invention consists in the general combination of parts and features to be described hereinafter.

The preferred embodiment of the invention is illustrated in the accompanying drawing and set forth in the accompanying specification, and the broad scope of the invention is set forth in the claims following hereinafter.

In the drawing, Figure 1 is a perspective indicating the construction and the manner of applying the device in practice. Fig. 2 is a side elevation showing a bar disconnected from the encircling band with which it is employed. Fig. 3 is a side elevation similar to Fig. 2, showing the other face of the said bar. Fig. 4 is a side elevation of the bar

shown in Figs. 2 and 3. Fig. 5 is a perspective showing one embodiment of the protecting member which I employ to prevent the metal bar from coming in contact with the limb. Fig. 6 is a perspective showing another embodiment of the protecting member.

Referring more particularly to the parts, 10 represents an encircling band which may be of any suitable material, such as elastic of a suitable length to encircle the limb below the knee. With this band I employ a metallic portion which may be in the form of a supporting bar 11 which is preferably formed of a narrow elongated bar of thin metal, said bar preferably having at its upper end two oppositely disposed eyes or slots 12. The bar is attached to the band by pulling the loose ends 13 of the band through the slots in succession and in opposite directions. When attached to the band in this way the bar will prevent the loose ends from pulling out of the slots so that when adjusted the diameter of the encircling band will be maintained. However, the encircling band may be adjusted to any size desired by manipulating the ends 13 with one's fingers in either direction at the slots. Any suitable engaging means may be employed for securing the bar to the hose, a portion of which hose is indicated at 14. But this engaging means is preferably so constructed as to enable the sleeve to hold it out of contact with the limb. This engaging means is therefore preferably rigid with the bar and may be produced simply by turning up the lower end of the bar so as to form a hook 15, and this hook is preferably formed with serrations or teeth 16 to engage the material of the hose 14.

In order to prevent any metal part from coming in contact with the flesh of the limb I prefer to provide a protecting member 17 which extends on the front and rear faces of the bar 11 and covers the side of the metallic portion which is disposed near the limb. This protecting member is preferably in the form of a simple flat sleeve such as that shown in Fig. 1. This sleeve should be slid onto the bar 11 from the upper end thereof before the band 10 is attached, and if the sleeve tended to move downward it would be prevented at its lower end from sliding off of the bar by the aforesaid engaging means or hook 15. Likewise if the sleeve tended to move upwardly on the bar, band 10 would prevent such a movement. The

protecting member applied to the bar before attaching the band is illustrated by the dotted line 17^a in Fig. 4. This protecting member is preferably formed of a non-absorbent material and a material which is clean and inviting in appearance. For this purpose I prefer to use white celluloid. This material is clean in appearance and non-absorbent, so that it will not take up perspiration and it can be readily cleaned, if desired, with a moist cloth. By forming the protecting member 17 of celluloid it is particularly well adapted for receiving an inscription or legend, which may be printed upon it in ink, and on account of the white color of the celluloid the legend or printed matter is very conspicuous, and therefore the protecting member is admirably adapted for carrying advertisements, such as the name of a manufacturing company. If desired, the protecting member may be formed of a sleeve, such as the sleeve 18 illustrated in Fig. 5, presenting an opening or window 19 in its forward face, and this form of the protecting member is admirably adapted for use with the bar 11 when bearing initials 20 on its face, such as shown in Figure 3. This embodiment of the invention may be adopted where the bar 11 is of a better quality. With the initials directly on the bar the opening 19 operates as a window, and the celluloid gives the effect of a frame around the initials.

I am aware that it is old to provide a garter with a flat bar adapted to engage the hose at its lower end, and having a limb-encircling band secured through the upper end of the bar to support the same. This form of garter was practical and efficient, but, owing to the modern style of dressing wherein short drawers are worn, this one time practical and efficient garter is today obsolete and unsalable. My improvement, though extremely simple, renders this garter available and useful to many persons who otherwise would not wear a garter of this type.

I do not claim to be the first to cover a metal part to prevent its touching the flesh, but I do claim to have produced a garter, the features of which all coöperate in such a way that certain parts of the metal may be left exposed. By leaving these parts exposed, the application of the protecting covering is rendered so simple and inexpensive that a very practical and salable garter is produced without entailing any substantial increase in cost of manufacture.

I do not confine myself to the particular forms of the protecting member illustrated, and I may adopt other forms for the same, such, for instance, as that shown in Fig. 6, in which the protecting member 20 is in the form of an elongated flat plate 21 having its edges bent around and forming flanges

22 engaging the side edges of the bar. It is understood, however, that when in this form the flanges 22 permanently hold the position in which they are illustrated, so that the protecting member may be applied to the bar by sliding it over the upper end of the bar in the manner suggested above. The protecting member is preferably long enough to extend from the hook 15 to the band 10, so that it is prevented by the hook 75 and the band from working along the bar. In other words, the band and the hook operate to retain the protecting member on the bar.

It will be observed that the protecting 80 member 17 extends upwardly on the bar to a point near the slots 12 and hence the upper portion of the metal bar is left exposed. However, the band 10 is attached to the bar in such a way that it will hold this exposed 85 end of the bar out of contact with the limb. For this purpose the band is preferably attached to the bar in the manner illustrated, that is, one end of the band passes through one of the slots from the inner side of the 90 bar and then through the other slot from the outer side; the other end of the band is passed through the slots in the same way but in a reverse direction. This arrangement accomplishes the double effect of keeping the upper end of the bar away from the limb but permitting easy adjustments of the band.

In constructing the garter, the sleeve member may obviously be made of any suitable non-metallic material, such as the materials named above. It is also necessary that the slots in the metallic member and the band should have a relation such that the band will operate to hold the exposed 100 end of the metallic member out of contact with the limb. This is accomplished by placing the slots as illustrated close together so that where the band projects at the back of the metallic member it touches the limb 105 and holds the metallic member off of the limb.

It is understood that the embodiment of the invention set forth herein is only one of the many embodiments or forms this 115 invention may take, and I do not wish to be limited in the practice of my invention nor in my claims to the particular embodiment set forth.

What I claim is:

1. A garter having a metallic portion with engaging means for engaging the hose, and a non-metallic covering for said metallic portion holding the lower portion of said metallic portion out of contact with the limb, said metallic portion having an exposed portion with eyes projecting beyond the upper end of said covering, and an encircling band to pass around the limb and having its ends threaded through said eyes 130

and projecting on the inner side of the said exposed portion so as to engage the limb and thereby hold said exposed portion out of contact with the limb, said band and said engaging means lying adjacent the ends of said covering whereby they would prevent an upward or downward displacement of said covering.

2. In a garter, the combination with a bar 10 having longitudinal slots in its upper end and having its lower end upturned and provided with hose engaging teeth, of a limb-encircling band secured through said longitudinal slots for supporting the bar, and a 15 non-metallic sleeve mounted on the bar so as to prevent contact thereof with the limb,

said sleeve engaging at its lower end the upturned lower end of the bar whereby the said upturned end would retain the sleeve from normal downward displacement, said 20 sleeve terminating at its opposite end adjacent said longitudinal slots whereby said band would prevent upward displacement of the sleeve.

In testimony whereof I have hereunto set 20 my hand in presence of two subscribing witnesses.

JOSEPH WILMOT SMITH.
